UNITED STATES PATENT OFFICE.

HENRY B. SKEELE, OF CHICAGO HEIGHTS, ILLINOIS.

TILE-FASTENER.

SPECIFICATION forming part of Letters Patent No. 721,246, dated February 24, 1903.

Application filed July 5, 1901. Serial No. 67,145. (No model.)

To all whom it may concern:

Be it known that I, HENRY B. SKEELE, a citizen of the United States, residing at Chicago Heights, in the county of Cook and State 5 of Illinois, have invented certain new and useful Improvements in Tile-Fasteners, of which the following is a specification.

My invention relates to that class of clay products known as "roofing-tiles," which in a 10 variety of forms and patterns are extensively used to form the outer coverings of roofs of buildings; and, more specifically, it pertains to means for securely fastening the contiguous overlapping or interlocking end portions 15 of adjacent tiles when in operative position to each other and to the roof. Owing to the refractory and somewhat brittle nature of this class of roof-coverings and the ornamental and more or less complicated patterns in which 20 tiles, especially the interlocking variety, are often molded, the usual fastening means, as a nail or screw passed through the body of the tile and directly into an underlying purlin or other element of the roof-frame, has proved 25 inapplicable in connection with tiles of this class, except the plain flat patterns.

The object of my present invention therefore has been to provide a simple, inexpensive, and reliable fastening device adapted to 30 not only bind together the overlapping ends of the tiles, but to also at the same time fasten the latter to the underlying purlins or other elements of the roof-frame on which the tile covering is directly supported.

35 My invention is represented in the accompanying drawings, in which—

Figure 1 is a perspective view of a fragment of a tile-covered roof structure viewed from beneath and illustrating my improved fastener and the manner in which the same unites 40 the overlapping ends of the tiles and binds the latter to the underlying roof-frame, and Fig. 2 is a detail in side elevation of my novel fastener shown in operative position in Fig. 1.

45 Referring to the drawings, B designates one of the transverse purlins of a roof-frame.

C designates as an entirety a form of roofing-tile in connection with which my invention may advantageously be employed, the 50 tile herein illustrated being substantially of the pattern and construction shown in the United States patent to Wilhelm Ludowici,

No. 283,126, granted August 14, 1883. For the sake of clearly illustrating the application and use of my invention I have shown portions of three coöperating tiles, the lower downwardly-turned margin c of the upper tile overlapping and interlocking with the upwardly-turned upper margins c' of two laterally-adjacent lower tiles. The said margin c 55 of the upper tile rests in a corresponding transverse groove formed across the outer faces of the two lower tiles near the upper ends thereof, whereby the tiles are mutually interlocked against longitudinal movement relatively to each other, while they are held against such movement relatively to the supporting-frame of the roof by means of transverse ribs c², formed across their under sides near the upper end thereof, said ribs overhanging the purlins B in the manner plainly 60 shown in the drawings.

Referring now more specifically to the improvements forming the subject of my present invention, it will be apparent that some 75 means must be provided for securing the overlapping end portions of the tiles against outward movement or separation relatively to each other and to the supporting-frame of the roof. In order to effect this result, I form in 80 the molding operation at an appropriate place on the under face of each tile a lug D, having in one side thereof a hole d of a suitable size and depth to receive one end of a bent wire fastener, as hereinafter described.

85 E' represents the fastener proper, which consists simply of a single piece of suitably-bent heavy stiff wire. This fastener has an upper inwardly-bent end section e², adapted to enter the holes d in lug D, and it has a 90 lower somewhat-extended end section e³, parallel, or substantially so, with the end e² and adapted to be passed under the purlin B in the manner plainly shown in Fig. 1. The intermediate body portion e⁴ of the fastener is 95 preferably curved at its lower portion to permit the fastener to conform to the upwardly-curved upper end of one of the lower tiles which it may engage, such curve also effecting an economy in the material required for 100 the fastener.

From the foregoing it will be seen that I have devised a simple, effective, and inexpensive fastener for the purposes stated, re-

quiring but a minimum of material and capable of easy and quick application.

It will be obvious that the utility of my invention is by no means limited to the particular form of tile shown and described, but may be applied with equal advantage to any other form of overlapping tile, nor is the fastener limited to the precise form herein shown, except to the extent indicated in the claims, 5 provided it be formed from a single piece of wire or equivalent material, the ends whereof are suitably bent to easily and removably engage members which are to be held thereby against separation, the fastener being unattached to the parts intermediate its ends.

The fastener will preferably be made of steel wire, in view of the elastic quality of the latter, whereby when in operation it tends constantly to draw the parts snugly together.

20 I claim as my invention—

1. The combination with an upper and a lower tile, the lower end of the former overlapping the upper end of the latter, and the upper tile being provided with a recessed lug 25 on its under surface near the lower end thereof, of a readily insertible and removable fastener formed from a single length of heavy elastic wire having its upper end suitably bent to slidingly enter the recess of said lug 30 and its lower end suitably bent to similarly engage beneath an underlying member of the

roof-frame, and otherwise unattached to said parts, thereby clamping said tiles securely to each other and to the frame of the roof, and being removable by simply withdrawing the 35 same, substantially as described.

2. The combination with a pair of overlapping interlocking tiles, the lower of which has formed across its under surface near its upper end a transverse rib whereby it is supported from an underlying purlin and the upper of which has formed on its under surface near the lower end thereof a recessed lug, of a readily insertible and removable fastener formed from a single length of heavy elastic 45 wire having its upper end bent to slidingly enter the recess of said lug, its intermediate body portion curved to snugly overlie the upper end of the lower tile, and its lower end bent to lie substantially parallel with its upper end and slidingly engage beneath the under face of the purlin, and otherwise unattached to said parts, thereby clamping said tiles against outward and longitudinal displacement relatively to each other and to the 50 roof-frame, and being removable by simply withdrawing the same, substantially as described.

HENRY B. SKEELE.
